OTTO H. HARTMANN, OF CASSEL-WILHELMSHOEHE, AND WILHELM JUNG, OF CASSEL, GERMANY, ASSIGNEES TO SCHMIDTSCHE HEISSDAMPF GESELLSCHAFT M. B. H., A GERMAN CORPORATION, OF CASSEL-WILHELMSHOEHE, GERMANY.

LOCOMOTIVE BOILER AND METHOD OF OPERATING THE SAME.

Application filed May 9, 1925, Serial No. 29,040, and in Germany May 14, 1924.

Our invention relates to locomotive boilers in which provision is made for generating live steam at a plurality of different pressures in the respective sections of the 5 boiler. Our improvements have been designed primarily for use in conjunction with a locomotive in which live steam of two pressures is employed, the high-pressure section embodying a water-tube fire-box, while the 10 low-pressure section consists of a smoke-flue longitudinal boiler of the customary type. In our present invention, the feed water is delivered to the high-pressure section, and from the latter the excess feed water 15 is conveyed to the low-pressure section or sections, that is to say, to the longitudinal boiler, in the particular case mentioned above. This arrangement effects a great simplification in the supply of the feed water, since a single feed pump will suffice for 20 supplying water to all pressure stages or sections of the steam generator plant, and this feed pump may also have the function of causing the water to flow through the feed water heaters. We thus avoid the complicated operation which would be inevitable 25 if two or more separate feeding devices were employed for the different pressure stages.

The water-tube fire-box, constituting a 30 high-pressure steam generator, will thus always receive fresh feed water, and not water taken from the low-pressure longitudinal boiler and contaminated by boiler-scale. Since it receives relatively pure water, the 35 fire-box boiler section, which contains a comparatively small amount of water, will not boil over, as is likely to occur when this boiler is supplied with impure water.

The new arrangement is particularly advantageous when the feed water is highly heated, for instance to 160° centigrade and more, before its admission to the fire box. This procedure will insure elimination of the substances producing boiler-scale, before the feed water reaches the fire-box, and will prevent or retard the fouling of the steam-producing, heating surface of the fire box, so that this surface will require cleaning only at long intervals. Preferably the 50 feed water is first heated to about 100° centigrade by the exhaust of the engine and then

passed through another heater in which live steam from the low-pressure boiler constitutes the heating medium. The substances which form boiler-scale will then remain in 55 the feed water heater. The second heater is preferably placed at a relatively high level so that the water formed by condensation may flow back to the longitudinal boiler by gravity, that is to say, without the use of 60 a pump or other propelling device.

Preheating the feed water to a high temperature insures the same advantage as when water from the low-pressure boiler is fed directly to the high pressure boiler. That 65 is to say, by far the greater portion of the heat conveyed to the water in the fire box will be utilized, not to bring such water to a higher temperature, but to convert it into steam. The proportion of steam produced 70 in the high pressure boiler (relatively to the total amount of steam generated) will thus be increased.

The overflow of the feed water from the high pressure section to the low pressure 75 boiler is preferably controlled automatically, for the sake of simplicity, for instance, by means of a float. In that event, notwithstanding the use of a plurality of pressures, the fireman will have to watch only one wa- 80 ter gauge and attend to a single pump. Since a needless consumption of power is in- 85 volved in the overflow of the feed water to the longitudinal boiler, when two boiler pressures are employed, it is desirable to drive the feed water pump as economically as possible. For this purpose, the feed wa- 90 ter pump is operated by high pressure steam, and while the engine is under way the ex- 95 haust steam from the feed water pump is mixed with the steam in the receiver; when the engine is standing still, such exhaust steam is led into the low-pressure boiler. In this latter event, it is advisable to inter- 100 pose an oil separator in the exhaust piping of the auxiliary which drives the feed water pump. Instead of using high pressure steam for the operation of the feed water pump, we might take steam for this purpose from the low pressure boiler and use the exhaust of the auxiliary driving the feed water pump, for heating the feed water in

and well-known or approved manner. With this mode of operation, the entire energy of the high pressure steam will be used for driving the engine.

5 It is preferable, furthermore, in order that superheat may be available at all times for the operation of the feed water pump, to provide a separate superheater or superheater section for this purpose. Instead of 10 conducting the feed water, after it has abstracted heat from the exhaust steam of the engine, through a separate device constituting a second feed water heater, to effect a further increase in the temperature of the 15 feed water, we might lead the feed water, preheated by the final exhaust, through a system of coils or pipes arranged in the longitudinal boiler.

A satisfactory form of our invention is 20 shown, as an example, in the accompanying drawings, in which Figs. 1 and 2 represent, in side elevation, a locomotive embodying our invention in a form in which live steam of two different pressures is generated.

25 At 1 we have shown the fire box, the walls of which consists of water tubes, and at 2 the longitudinal boiler, which may be of any well known or approved type. The fire box walls constitute part of the water space 30 of a high-pressure boiler or boiler section, which water space is separate from the water space of the low-pressure boiler or boiler section 2. The water tubes of the fire box are utilized for the generation of steam 35 in a container 3, either by being connected directly with the water space of said container, or by indirect heating, the hot water from the fire box tubes circulating through coils located in the water space of the container 3, the interior of said coils having no 40 communication with the interior of the container. The low-pressure boiler 2 has a steam dome 5.

The steam spaces of the container 3 and 45 of the boiler section 2 are not in direct communication with each other, so that it becomes possible to produce in the container 3, live steam of a pressure (for instance, sixty atmospheres) considerably higher than that 50 (for instance, fifteen atmospheres) generated in the longitudinal smoke flue boiler 2.

The feed water is delivered by a pump 6 to the container 3 along the path indicated below. The auxiliary engine 11 which operates 55 the feed pump 6 is driven by high pressure steam taken from the container 3 through a pipe 12. While the locomotive is under way, the exhaust from the auxiliary 11 passes through a pipe 13 to the receiver 14 of the main engines. When the locomotive is standing still, this exhaust may be conducted to the low-pressure boiler 2, as has been mentioned above. In this case, since it is undesirable to allow the oil contained 60 in such exhaust steam to reach the

low pressure boiler, we prefer to interpose oil-separators 13" of any well-known or approved type in the pipe connection 13' from the auxiliary 11 to the low pressure boiler 2. The pump 6 takes the feed water from the 70 tender (not shown) through a suction pipe 15 and forces it through a pipe 16 into a surface heater 17, heated by the exhaust of the main engines, which is supplied through a pipe 18. Water resulting from condensation of this exhaust steam is discharged through a pipe 19. In the heater 17, the feed water is heated to about 100° centigrade, and then passes through a pipe 20, controlled by a check valve 30, to a surface 75 heater 21, the heating medium for which consists of (low-pressure) live steam taken from the longitudinal boiler 2 through a pipe 22. The heater 21 is placed at a relatively high level, so that the water resulting 80 from the condensation of the steam which heats the feed water at 21, may pass to the low pressure longitudinal boiler 2 through a pipe 23 by gravity, that is to say, without the provision of additional propelling devices. Instead of passing the heated feed water through this second heater 21, we might cause it to flow from the pipe 20 through a branch conduit 20', controlled by a valve 31, into a system of pipes or coils 85 20' arranged within the low-pressure longitudinal boiler, preferably in the steam space thereof or, obviously, we might pass the water through both heaters in parallel as shown in the drawing. By operating the 90 valves controlling the flow from the pipe 20 into heaters 20' and 21, the water can be made to pass into either or both of said heaters as desired. Of course, when only heater 20' is used, the flow of steam from 95 dome 5 to heater 21 will be stopped as by means of a valve 35. In the heater 21 or 20', the temperature of the feed water is raised materially above the temperature (100° centigrade) to which it has been heated in 100 the heater 17. From the heater 21 or 20' or both of them a pipe 24 controlled by a valve 32 delivers the feed water to the steam space of the container 3. The feed water in coils 20' passes through a conduit 24' which 105 opens into the pipe 24 and is controlled by a valve 33. The excess feed water passes from the container 3 to the low pressure boiler 2, but inasmuch as different pressures prevail in the two boiler sections, the communication is but temporary, a float 25 or equivalent device controlling the overflow 26 from the container 3 to the low pressure boiler 2. In other words, the overflow is normally sealed.

115 As we have mentioned above, instead of operating the auxiliary engine 11 of the feed water pump 6 with high-pressure steam taken from the container 3, we might actuate it with steam taken from the low-pres- 120

sure boiler 2 through a pipe 12'. It is also desirable to provide a separate superheater for the steam on its way to said auxiliary engine 11. The "saturated" or "wet steam" header of this separate superheater is indicated at 2" and the superheated steam header at 2'. From the latter, a pipe 12" conveys the superheated steam to the auxiliary engine. These modifications and various others may be made without departing from the nature of our invention as set forth in the claims.

We claim:

1. A locomotive boiler having a high pressure boiler section which includes a water tube fire-box, a low pressure section formed by a longitudinal smoke flue boiler, said sections being normally out of communication so as to enable different steam pressures to be maintained therein for supplying live steam at different pressures, a conduit for supplying feed water to the high pressure boiler section in excess of the normal demand of such section, and a normally sealed connection for delivering the excess feed water from the high-pressure section to the low-pressure section.

2. A locomotive boiler having a high pressure boiler section which includes a water tube fire-box, a low pressure section formed by a longitudinal smoke flue boiler, said sections being normally out of communication so as to enable different steam pressures to be maintained therein, a conduit for supplying feed water to the high pressure boiler section, and a float-controlled, normally closed overflow device for the passage of water from the high-pressure section to the low-pressure section, said device constructed and arranged to insure a steam space in said high pressure section.

3. A locomotive boiler having a high pressure section, a low-pressure section for supplying live steam at different pressures, a conduit for supplying feed water to said high pressure section in excess of the normal demand of such section, and a normally sealed connection for delivering the excess feed water from the high-pressure section to the low-pressure section.

4. A locomotive boiler having a high pressure section, a low-pressure section, conduits connected to said boiler sections to withdraw live steam of different pressures therefrom, a conduit for supplying feed water to said high pressure section in excess of the normal demand of such section and a float-controlled, normally closed overflow device acting in response to the variations in water level in the high pressure boiler for controlling the passage of excess water from the high-pressure section to the low-pressure section.

5. The method of supplying feed water to boiler sections in which live steam of differ-

ent pressures is produced, which consists in supplying the feed water to a high-pressure section in excess of the normal demand of such section and then conveying the excess feed water from such high-pressure section to a low-pressure section.

6. The method of supplying feed water to boiler sections in which live steam of different pressures is produced, which consists in supplying the feed water to a high-pressure section in excess of the normal demand of such section and keeping such section out of communication with the low-pressure section while the water is below a certain level in said high-pressure section, and conveying excess feed water from the high-pressure section to the low-pressure section whenever the water rises above said level in the high-pressure section.

7. The method of operating a locomotive engine with the aid of a boiler having two sections generating high-pressure steam and low-pressure steam respectively, which consists in first heating the feed water to about 100° centigrade by the exhaust of the locomotive engine, then further heating such feed water by live steam taken from the low-pressure section, and thereupon passing the feed water thus heated to the high-pressure boiler section.

8. A locomotive boiler having a high-pressure section and a low-pressure section, and a feed water heater having a connection to heat it by live steam taken from the low-pressure boiler section, said heater being located at a level above the said low-pressure section, and having an outlet connection through which the water resulting from the condensation of the heating steam may flow to said low-pressure section by gravity.

9. A locomotive boiler having a high-pressure section and a low-pressure section, a feed water heater having connections for heating it with the exhaust steam of the locomotive engine, and a second feed water heater, interposed in the path of the feed water from said first heater to the discharge of such water into the boiler, and consisting of a tube system located within the low-pressure boiler section.

10. A locomotive boiler having a high pressure boiler section which includes a water tube fire-box, a low pressure section formed by a longitudinal smoke flue boiler, said sections being normally out of communication so as to enable different steam pressures to be maintained therein for supplying live steam at different pressures, a conduit for supplying feed water to the high pressure boiler section in excess of the normal demand of such section, a preheater for said feed water, and a normally sealed connection for delivering the excess feed water from the high pressure section to the low pressure section.

11. A locomotive boiler having a high pressure section, a low pressure section for supplying live steam at different pressures, a conduit for supplying feed water to said high pressure section in excess of the normal demand of such section, a preheater for said feed water, and a normally sealed connection for delivering the excess feed water from the high pressure section to the low pressure section. In testimony whereof we have hereunto set our hands.

10
